UNITED STATES PATENT OFFICE.

ERNEST BOCCINO, OF PASSAIC, NEW JERSEY, ASSIGNOR TO UP TO DATE MANUFACTURING CO., INC., OF JERSEY CITY, NEW JERSEY.

SOUND-EMITTING DEVICE.

Application filed January 24, 1925. Serial No. 4,419.

This invention relates to improvements in sound emitting devices capable of producing a crying sound upon being maneuvered to cause its internal elements to change 5 their relative position.

One feature of the invention is in the provision of means which automatically modulates the sound produced, causing a difference in pitch between the earlier portion 10 of sound and the final or main portion.

A further purpose is to produce a device that is essentially simple and cheap to construct, instantly responsive to positional changes and dependent wholly upon gravity 15 in the performance of its functions.

These and other allied aims and objects are accomplished by the arrangement of parts in the structure hereinafter described and shown in the accompanying drawing, 20 forming a material part of this disclosure, and in which:

Figure 1 is a top plan view of a sound emitting device, made in conformity with the invention.

Figure 2 is a longitudinal sectional view taken on line 2—2 of Fig. 1.

Figure 3 is a plan view of the device showing the cover portion removed and looking in a plane indicated by the line 3—3 of 30 Fig. 2.

As shown in the drawing, the mechanism is enclosed in a thin metal casing 10, an elongated rectangle in shape, having a depression 11 and, near its raised upper edges is 35 an outstanding bead 12.

Resting on the bead 12, when in position on the casing, is a cover 13 having a raised rim 14, forming a depressed panel 15 containing a plurality of fancifully grouped 40 perforations 16, larger openings 17 being symmetrically disposed.

Fixed in the depression 11 is a flat block 18 secured by a screw 19, this block forming the base member of a bellows, the upper or 45 movable member 20 of which is secured by a hinge 21, such as a flexible strip of leather attached to the adjacent ends of each member.

The bellows further include a thin flexible element 22, such as leather or textile fabric rendered air resistant, this material being cemented to the edges of the members 18 and 20 so that no air can leak.

At the end of the upper element 20, opposite the hinge, is a weight 23 of such

character as to normally close the bellows from an open position, as shown in the broken lines in Fig. 2, to the closed position shown in full lines therein.

At about the center of the upper member 20 is an opening 24, over which is a reed 25, fixed on a plate 25' its projecting ends being fixed to the top of the member by any preferred means.

An inverted metallic cup 26 is disposed 65 over the opening 24, covering the reed 25, but avoiding contact with the same, the edge of the cup being held by an adhesive on the upper surface of the member 20.

The cup 26, has a relatively large perforation 27 at its center and at one side a minute 70 vent perforation 28 permitting a limited passage of air, these perforations constituting major and minor openings.

Secured to the inner surface of the end 75 wall of the cover 13, adjacent the hinge, is the flanged foot 29 of a resilient leaf 30 extending normally straight and parallel within the casing to project over the opening 27 when the bellows is expanded, as in the 80 broken lines in Fig. 2, covering the opening and preventing the passage of air during the earlier part of the bellows movement when closing, air at that time passing through the perforation 28.

In operation the device is raised and inverted from the position shown in Fig. 2, 85 the weight 23 causing the bellows to expand, air being admitted to its interior through the openings 27 and 38, the former being closed during the latter part of the opening by the leaf element 30.

Upon reversing the device, into the position shown, air is forced out of the bellows by reason of the weight, the air passing 90 through the opening 24, causing the reed 25 to vibrate and produce sound of a certain intensity or tonality, the air escaping into the cover through the small perforation 28; later, when the larger opening 27 is released 100 from the spring leaf, 30, the bellows closes more rapidly and the volume of sound is increased and changed, producing a different note, the sounds eventually escaping into the atmosphere through the openings in the 105 cover.

Thus it will be seen that the cover carried flexible leaf 30 operates automatically to modulate the sound produced and also to accelerate the initial closing of the bellows. 110

Although the foregoing is descriptive of the preferred embodiment of the invention, it will be apparent that minor changes may be made in its construction, without the exercise of invention or conflicting with the scope of the claims hereto appended.

Having thus described my invention what I claim as new and desire to secure by Letters Patent, is:—

1. A sound emitting device comprising an oblong rectangular casing having a depression in its bottom, a perforate cover removably engaged on said casing, a bellows having one element fixed in said casing depression, the movable element of said bellows being hinged at one end and having a central opening and carrying a weight, a reed disposed in the opening, an inverted cup fixed on said movable element to cover said reed and opening, said cup having a major and minor perforation, and a flat resilient member carried by said cover at the end of said casing adjacent the bellows hinge adapted to close the major perforation therein when the hinged portion of the bellows is partially raised.

2. A sound emitting device comprising a rectangular casing having a centrally depressed portion, a perforate cover tight fitting the casing, a bellows fixed in the depressed portion of the casing, said bellows having a hinged element containing an opening, a weight on said hinged element, a vocal sound producer including a reed fixed on said element over the opening, a cup enclosing the vocal element and having a central relatively large opening and a small opening,

and means carried by said cover to close the central opening at the initial stage of bellows closure.

3. A sound emitting device comprising an oblong rectangular casing, a cover removably engaged on said casing, a stop on said casing to limit the cover, a bellows in the casing, said bellows being gravity operated upon reversion, a reed vibrated by air from the bellows, an inverted cup permanently secured on said bellows to cover the reed, said cup having an air passage, and a spring leaf carried wholly by said cover to modify the transit of air through the passage during the initial exhalation of air from said bellows, said leaf being in contact with the movable part of said bellows when open to cover the passage therein.

4. A sound emitting device comprising a casing having a cover, a bellows in the casing, there being an opening in the movable member thereof; a reed vibrated by air from the bellows disposed adjacently over the opening, a convex cover over the reed and opening, said convex cover having two perforations of unlike area; and a flat spring leaf having a part secured to said cover and another part adapted to restrict the passage of air from the bellows through the larger of the mentioned openings when the bellows is fully expanded and during the earlier part of its closing movement, all of said elements being enclosed within the casing.

Signed at New York, in the county of New York and State of New York, this 23d day of January 1925.

ERNEST BOCCINO.
